UNITED STATES PATENT OFFICE.

PAUL MAYER, OF VIENNA, AUSTRIA.

DEVICE FOR HOLDING AND APPLYING COSMETICS AND THE LIKE.

Application filed August 3, 1926, Serial No. 126,821, and in Austria May 5, 1926.

- This invention relates to a device for holding tubular articles, particularly, toilet preparations and cosmetics in stick form, such as lipsticks, color, pencils, soap, and the like.
- 5 It is an object of this invention to provide a device in which the article may be normally kept within a container, but extended from the container in a practical form for use, by the removal of the cover.
- 10 It is a further object to produce a device of the character described, in which the closed container may be opened and the preparation exposed for use, and in which it may be also used and again enclosed within the container by the manipulation of one hand.
- 15 It is a further object of the invention to provide a device in which such preparations, particularly when they are somewhat soft and liable to be softened by heat, may be caused to project from a container only so far as is necessary to permit their use and retained in that position during use, without liability of being unduly softened by contact of the unused portion with the fingers.
- 20 It is a further object to produce a container of the character described, in which the removal of the lid will automatically cause the projection of the article, and in which, after use, the lid will be guided into its position to close the container.
- 25 Within the scope of this invention the tubular support may be made substantially of the same diameter as the bore of the casing, so that it slides freely therein and is guided thereby, and this support is adapted to grasp the base of the stick without extending upwardly on the sides thereof. The cap may be arranged, moreover, so as to be guided for movement along the axis of the tube during the withdrawing and replacing operation and snaps readily into this axial position at either end of the casing. The cap retaining means is, moreover, preferably pivotally connected to the support exterior to the tube, so that the removal of the cap by axial movement automatically draws the article from the casing and thereafter, if the cap be swung to an axial position at the other end of the casing, the amount of protrusion of the article may be determined by the axial movement of the cap.
- 30 Other objects of the invention will in part be obvious and will in part appear herein-after.
- 35 According to this present invention the lid of the holder is articulated to the plunger member or the like which is guided inside the holder, so that during the removal of the lid, the article is gradually drawn out of the holder, and when the article is in position for use the lid can be swung out of the way. In a preferred embodiment, the lid and plunger are connected by means of an arm which can be folded over the holder when the article is in position for use, and is thereby kept out of the way.
- 40 In order more clearly to understand the invention reference is made to the accompanying drawings which illustrate by way of example two typical embodiments thereof, for use with a lipstick, and in which:
- 45 Figs. 1 to 3 represent one embodiment, Fig. 1 showing the holding device, in the closed position, as a side elevation; Fig. 2 a similar view of the holder with the lipstick protruding, and Fig. 3 a front elevation of the holder in position for use. Fig. 4 shows another embodiment of the holder, in section.
- 50 Fig. 5 is a cross section taken through Fig. 1 at substantially the point where the pins connect with the cosmetic.
- 55 In the embodiment illustrated in Figs. 1 to 3, the holder consists, for example, of a tube 1, closed at one end and provided with a longitudinal slot 2 in diametrically opposite positions on each side. Adjustably mounted inside the tube 1 is a clip 3 (plunger), which forms the carrier for the lipstick 4 or the like inserted therein. The tube 1 is closed by a lid 7, in the form of a cap, which is articulated to the clip 3 by means of a bow arm 6, the connection being effected by means of pins 5 guided in the slots 2 of the tube 1. In order to use the lipstick, the cap 7 is drawn upwards into the position shown in Fig. 2 and the bow 6 (here shown by dotted lines) is swung down sideways so that it can serve as a handle for gradually drawing out the lipstick. When the latter is being used, the bow can also be folded into the position shown in Fig. 3, in which the tube 1 lies inside the bow 6, and the cap 7 can be pushed over the bottom of the tube. In a practical manner, it is desirable that the cap be constrained to move in an axial direction when opposite either end of the tube, so that it may be readily brought into place with one hand, and to this end, the container and the arms are preferably mutually so shaped as to be resiliently held in a position to be guided for relative axial movement, this

resilient holding being such as to permit the cap to be swung to either end of the tube and to be snapped into alignment and be resiliently held at either end. A practical method of 5 accomplishing this result when the tube is curved in section, comprises conforming the arms 6 to the external curved shape of the tube 1 and making the arm of spring material, so that when in the two end positions, as 10 shown in Figures 1 and 3 respectively, they snap into place.

When the cylindrical tube 1 is used, the arms 6 may be adapted to fit same, and, being curved in cross section, can be made springy, 15 so that, when in the two end positions as shown in Figs. 1 and 3 respectively—they snap into place.

In the embodiment shown in Fig. 4, the clip 3 engages with pins 5' which pass through 20 the slots 2 of the tube and are formed by bending the ends of the bow 6, the central portion of which is in the form of a cap 7.

The holder tube, which is also adapted for use as an applying device, may be of any 25 desired cross sectional shape, round, oval, or angular.

By reason of the fact that the connection between the cap and the cosmetic support is 30 outside of the container, the cosmetic support may be moved to protrude the cosmetic varying amounts, while the cap is removed, and moreover, the arms which connect the cap with the support are in no danger of abrading the cosmetic either to soil the fingers or to clog 35 the mechanism. Moreover, when the cap is in place the arms cooperate with the cap completely to close the mechanism by protecting the slot. Thus the entrance of dust or other foreign matter into the interior of the container is precluded. Moreover, by reason of 40 the fact that the cap is rigid upon the arms the cap itself is guided into position to close the container when the arms are swung into alignment with the tube.

45 The herein-described holder may obviously also be used for other preparations or articles, and the clip or plunger 3 may be integral with the article to be movably mounted in the tube 1 or may be formed by said article itself.

50 What I claim is—

1. A holder for cosmetic, a cosmetic support adjustably movable in the holder, and a cover connected to said holder for movement to either end of the holder, said support operatively connected to the cover for being adjusted by movements of said cover irrespec- 55 tive of the position of the cover.

2. A holder for cosmetic having an opening, a cosmetic support adjustably movable 60 in said holder, and a cover connected to said holder for movement to either end of the holder, shiftable to position either in or out of alignment with the cosmetic opening, the cover being operatively connected to said support 35 for adjusting the latter throughout the full

range of movement of the support relative to the holder irrespective of the position of the cover, the connection between the cover and the holder including a resilient arm coactive resiliently with the holder to restrain the movements of the cover.

3. A holder for cosmetic, a cosmetic support adjustably movable in the holder, said holder comprising a tube having an aperture through its side, and a cover connected to said holder for movement to either end of the holder, said cover operatively connected to said support for adjusting the latter irrespective of the position of the cover, the connection between said cover and holder passing through said aperture and including an arm for closing said aperture when the cover is closed.

4. A holder for cosmetic, including in combination a tube having an opening, a cosmetic support adjustably movable longitudinally in the tube, and a cover longitudinally and transversely movable to open and close the cosmetic opening in the tube, said cover being operatively connected to said support for adjusting the latter irrespective of the position of the cover and having a resilient arm slidably coactive with the outer wall of the tube yieldingly to restrain the movements of the cover.

5. A holder for cosmetic including, in combination, a tube having an opening and longitudinal slots, a cosmetic support adjustably movable longitudinally in the tube, and a support-adjusting cover longitudinally and transversely movable to open and close the cosmetic opening in the tube, said cover having arms resiliently in contact with the outer wall of said tube yieldingly to restrain them from said movements, the connection between said cover and support leading from said cover outside said tube, through said slots to said support.

6. A holder for cosmetic, a cosmetic support adjustably movable in the holder, and a cover, having connection to said holder for movement outside the holder to either end of the latter and having support-adjusting movement at either end, said holder having an aperture in its side wall, said connection including a cover-carrying arm coupled to said support through said aperture for pivotal movement relative to said support, and of a length permitting adjustment of said support to one of either of the ends of the holder when the cover is at the other end.

7. A holder for cosmetic, a cosmetic support adjustably movable in the holder, and a cover, having connection to said holder for movement outside the holder to either end of the latter and having support-adjusting movement at either end, said holder having an aperture in its side wall, said connection including a cover-carrying arm coupled to said support through said aperture for piv-

- total movement relative to said support, and of a length permitting adjustment of said support to one of either of the ends of the holder when the cover is at the other end, said arm being resilient and co-active with the holder to close said aperture when the cover is closed.
8. A holder for cosmetic including, in combination a tube having an opening and a longitudinal slot a cosmetic support adjustably movable longitudinally in the tube, a cover, longitudinally and transversely movable to open and close the cosmetic opening in the tube, having an arm connected through said slot to said support, adapted to close said slot when the cover is closed.
9. A holder comprising a holder tube having a slot in a side wall, a carrier member telescoping within said holder tube, a cover member having a device extending through said slot into engagement with said carrier member for operating said carrier member.
10. A holder for stick material comprising a holder tube having a slot in each side, a carrier member telescoping within said holder tube, a cover member having a cap and a pair of projecting arms straddling and fitting said holder tube, said holder tube and arms being curved in cross section, and pivot means extending through said slots connecting said arms and carrier member.
11. A holder for stick material comprising a holder tube having a slot, a carrier member telescoping within said holder tube, an operating member having a part connected to said carrier member, said part acting as a closure for said slot when said holder is closed.
12. A holder comprising a holder tube, a carrier member telescoping within said holder tube, a cover member having an arm disposed outside said holder tube, and means for connecting said arm and carrier member.
13. In a cosmetic stick container, in combination, an elongated casing open at one end and closed at the other end and having longitudinal slots in opposite sides thereof, a cover capable of placement over the casing opening, two oppositely disposed legs carried by the cover and exterior of the casing, a cosmetic stick carrier within the casing and longitudinally movable therein and pivotal means passing through the casing slots and connecting the legs with the stick carrier.
- In witness whereof I have hereunto signed my name.
- PAUL MAYER.
